(57) **CLAIM**

The ornamental design for electrical air freshner, as shown and described.

DESCRIPTION

FIG. 1 is a partially exploded view of the electrical air freshner comprising an assembly of an upper base, a body and a lower base, showing my new design;

FIG. 2 is a left side perspective view of the electrical air freshner showing my new design;

FIG. 3 is a top perspective view thereof;

FIG. 4 is a left side elevation view thereof;

FIG. 5 is a front view thereof;

FIG. 6 is a top view thereof;

FIG. 7 is a front elevation view of an assembly of the upper and lower bases of the electrical air freshner of FIG. 1, shown separately for clarity of illustration;

FIG. 8 is a side elevation view of FIG. 7;

FIG. 9 is a bottom view of FIG. 7;

FIG. 10 is a top view of FIG. 7;

FIG. 11 is a perspective view of FIG. 7;

FIG. 12 is a left side elevation view of the body portion of the electrical air freshner of FIG. 1 shown separately for clarity of illustration;

FIG. 13 is a front elevation view of FIG. 12;

FIG. 14 is a top view of FIG. 12;

FIG. 15 is a bottom view of FIG. 12;

FIG. 16 is a right side elevation of FIG. 12;

FIG. 17 is a rear elevation of FIG. 12; and,

FIG. 18 is a left side perspective view of FIG. 12.
